United States Patent Office.

CONSTANTINE HINGHER, OF NEW BRUNSWICK, NEW JERSEY.

Letters Patent No. 106,585, dated August 23, 1870.

IMPROVEMENT IN COATING METAL ARTICLES WITH INDIA RUBBER.

The Schedule referred to in these Letters Patent and making part of the same.

To all whom it may concern:

Be it known that I, CONSTANTINE HINGHER, of New Brunswick, in the county of Middlesex and State of New Jersey, have invented new and useful Improvements in Covering Metal Articles with India Rubber; and I do hereby declare that the following is a full, clear, and exact description thereof, which will enable others skilled in the art to make and use the same; reference being had to the accompanying drawing forming part of this specification.

This invention relates to improvements in covering buckles and other metal articles with India rubber, and consists in the employment of varnish, soap, or other substances which will expand under the action of heat, between the surface of the metal article to be coated and the coating of rubber, for preventing the India-rubber coating from shrinking away from the walls of the mold while confined in it in the vulcanizing process, which shrinkage is very damaging to the coating, which, not being confined upon the smooth surface of the mold, becomes rough, and requires considerable finishing after removal, and is often wholly ruined.

Figure 1 is a plan view of a buckle covered according to my improved process;

Figure 2 is a section of the same; and

Figure 3 is a plan of a buckle covered by the process now in use.

Similar letters of reference indicate corresponding parts.

A is the metal part of the buckle.

The line B represents a coating of varnish, soap, soft metal, or any other substance with which the iron may be coated, and which will expand or vaporize under the action of heat sufficiently to swell the covering C of India rubber out snugly against the walls of the mold or flask into which the article to be coated is placed for vulcanizing the covering of India rubber, and thereby securing it to the wire.

Buckles and other metal articles have been covered heretofore with coatings of India rubber, placed on

them while in a tacky state, and secured by vulcanizing in metal or other molds; but, owing to the shrinkage of the India rubber in vulcanizing, caused by the action of the heat, the coatings so applied are very apt to be ruined by the surface being irregular and rough, and by reason of cavities formed in them by air or gases collecting in spots under the skin, which are broken into in smoothing and polishing the surface, and, therefore, the manufacture of such articles has not yet been practically successful.

I have found that, by the use of substances between the skin of India rubber and the iron to be coated, which will swell under the action of heat, the said coverings may be swelled out snugly against the walls of the molds, and made very smooth and perfect on the exterior, so that, when removed from the molds, they require but little or no finishing. I have also found that, after the vulcanizing and the articles have become cooled, the shrinkage of the said substance does not cause any looseness of the India rubber. I therefore propose to make use of this improved means in connection with the process now employed.

Having thus described my invention,

I claim as new and desire to secure by Letters Patent—

The herein-described improvement in the process of covering metal articles with vulcanized India rubber, consisting in subjecting the articles, while undergoing a vulcanizing process in the molds or flasks, to the action of coatings of varnish, soap, or other substances, which will swell or expand by the action of the heat employed for vulcanizing the coverings of India rubber placed between the said metal articles and the said India-rubber coverings, substantially as specified.

The above specification of my invention signed by me this 22d day of July, 1870.

CONSTANTINE HINGHER.
